(57) CLAIM

The ornamental design for a pendant, as shown and described.

DESCRIPTION

FIG. 1 is a front view of the pendant of the present invention.
FIG. 2 is a rear view of the pendant of FIG. 1.

FIG. 3 is a right-side view of the pendant of FIG. 1.

FIG. 4 is a left-side view of the pendant of FIG. 1.

FIG. 5 is a top view of the pendant of FIG. 1.

FIG. 6 is a bottom view of the pendant of FIG. 1; and,
FIG. 7 is top, right-side perspective view of the pendant of

The broken lines shown in the drawings represent portions of the pendant and form no part of the claimed design.
